United States Patent Office

Des. 185,660
Patented July 14, 1959

185,660

CAN DISPENSING RACK

Charles W. Crookes, Hawthorne, Calif.

Application June 16, 1958, Serial No. 51,379

Term of patent 14 years

(Cl. D80—10)

Fig. 2

Fig. 3 is a top plan view thereof.

I claim:

The ornamental design for a can dispensing rack, substantially as shown.
